UNITED STATES PATENT OFFICE.

WILLIAM F. FREEMAN, OF GRAND RAPIDS, MICHIGAN, ASSIGNOR TO GRAND RAPIDS SHOW CASE COMPANY, OF GRAND RAPIDS, MICHIGAN, A CORPORATION OF MICHIGAN.

GARMENT-HANGER.

941,510.

Specification of Letters Patent. Patented Nov. 30, 1909.

Application filed December 18, 1908. Serial No. 468,177.

To all whom it may concern:

Be it known that I, WILLIAM F. FREEMAN, a citizen of the United States of America, residing at Grand Rapids, in the county of Kent and State of Michigan, have invented certain new and useful Improvements in Garment-Hangers; and I do hereby declare the following to be a full, clear, and exact description of the invention, such as will enable others skilled in the art to which it appertains to make and use the same.

My invention relates to improvements in garment hangers, and more particularly to such devices adapted to support a coat and trousers, and its object is to provide the same with certain new and useful features hereinafter more fully described and particularly pointed out in the claims, reference being had to the accompanying drawings in

which:

Figure 1 is an elevation of a device embodying my invention. Fig. 2 an enlarged detail of the trousers holder shown in elevation and partially broken away. Fig. 3 a transverse section of the same on the line 3—3 of Fig. 2. Fig. 4 the same on the line 4—4 of Fig. 2. Fig. 5 is a modification of the same, shown in side elevation with a part broken away. Fig. 6 a transverse section of the same on the line 6—6 of Fig. 5. Fig. 7 the same on the line 7—7 of Fig. 5. Fig. 8 is a modification of the pivot portion of the device shown in Fig. 2, in side elevation with a part broken away. Fig. 9 a transverse section on the line 9—9 of Fig. 8.

Like numbers refer to like parts in all of the figures.

1 represents the coat hanger portion of the device having downwardly and outwardly extended arms and provided with a hook 2 at the top for suspending the same upon any convenient support.

3 represents a brace bar extending between the respective ends of the arms and preferably consisting of a flat metal bar having its respective ends bent to conform to the under surface of the arms and secured thereto by screws 4. Beneath this brace bar is a supporting bar 5 pivotally connected to the same at one end and having a limited downward movement at the other end when the latter is released. This supporting bar 5 is preferably semi-cylindrical and arranged with its convex surface up-

ward to form a rounded surface of considerable width contacting the goods thereon, whereby no crease will be formed in a garment when supported thereby, being connected at the pivoted end by means of a T-head 7 extending through a slot in the supporting bar, which has a limited pivotal movement thereon. The arms of this T-head being spaced unequally from the brace bar and the arm nearest the end of the bar 5 being nearest the bar 3, when the bars 6 are parallel this arm only supports the bar 5, the other being such greater distance from the brace bar that the bar 5 may be lowered at one end to a suitably inclined position to receive the trousers or other garment. The movable end of this bar 5 is provided with a lateral recess 8, in which is inserted a knob 6 which knob, when in the recess, engages the concave under surface of the said bar and holds the same detachably secured parallel with the brace bar.

In the modification shown in Figs. 5, 6, and 7, the pivoted end of the supporting bar 5^a is pivoted between the arms of a yoke by a rivet 11 extending through the arms and through the said bar, the yoke being fixed to the brace bar, and the bars spaced apart a sufficient distance to permit the lowering of the other end of the bar 5^a before its pivoted end will strike the brace bar. The movable end of the bar 5^a is held in place by a hook 9 secured to the brace bar and extending alongside the bar 5^a and engaging one of the lower edges thereof as shown in Figs. 5 and 6.

In Figs. 8 and 9 a modified pivot support 90 is provided consisting of a flat lug 12 secured to the brace bar and extending through a slot in the supporting bar 5^b, in which slot it has a limited oscillating movement sufficient to permit the lowering of the bar 5^b, 95 which bar is pivotally supported by a rivet 13 extending through the lower edges of the bar 5^b and the lower end of the lug 12.

What I claim is:—

1. A garment hanger comprising downwardly extended diverging arms, a brace bar connecting said arms and attached thereto, downwardly projecting members fixed in the brace bar near its respective ends, and a supporting bar having a limited pivotal connection at one end to one member and detachably supported by the other member at the other end.

2. A garment hanger, comprising downwardly extended diverging arms, a brace bar connecting the said arms and attached thereto, a T head fixed in the brace bar, a semi-cylindrical supporting bar having an opening to receive the T head and supported at one end thereby and having a limited downward movement at the other end, and means for detachably connecting said other end to 10 the brace bar. 30
3. A garment hanger, comprising downwardly extended and diverging arms, a brace bar connecting said arms and attached thereto, a supporting bar beneath the brace bar, a T-head connecting said bars, said head being fixed in one bar and having an oscillating movement in the other bar, and a knob fixed in one bar and detachably engaging a lateral recess in the other bar. 15 40
4. A garment hanger, comprising downwardly extended and diverging arms, a flat brace bar connecting the said arms and attached thereto; a semi-cylindrical supporting bar beneath the brace bar and having a slot near one end and a lateral recess near the other end, a T-head fixed in the brace bar and extending through the slot in the supporting bar and also having a limited oscillating movement therein, and a knob 20 45
- fixed in the brace bar and detachably engaging the lateral recess in the supporting bar. 30
5. A garment hanger, comprising downwardly extended diverging arms, a flat brace bar connecting said arms and attached thereto, a semi-cylindrical supporting bar beneath the brace bar and having a longitudinal slot near one end and a lateral recess near the other end, a T-head fixed in the brace bar and inserted in said slot and also having arms unequally spaced from said bar, and a knob fixed in the brace bar and detachably engaging the said lateral recess. 35 40
6. A garment hanger comprising downwardly extended diverging arms, a flat brace bar connecting said arms and attached thereto at its respective ends, and a supporting bar beneath the brace bar concavo-convex in cross section and having its convex side next to the flat side of the brace bar, means for pivoting the bars to each other at one end, and means for detachably connecting the bars to each other at the other end. 50 55

In testimony whereof I affix my signature in presence of two witnesses.

WILLIAM F. FREEMAN.
